UNITED STATES PATENT OFFICE.

FELIPPE SABOIA BANDEIRA DE MELLO, OF RIO DE JANEIRO, BRAZIL.

ELECTRIC BATTERY.

1,179,903.

Specification of Letters Patent. Patented Apr. 18, 1916.

No Drawing.

Application filed February 23, 1916. Serial No. 79,891.

To all whom it may concern:

Be it known that I, FELIPPE SABOIA BANDEIRA DE MELLO, a citizen of the United States of Brazil, and resident of Rio de Janeiro, Brazil, have invented certain new and useful Improvements in Electric Batteries, of which the following is a specification.

This invention relates to primary electric batteries.

The leading feature of the invention consists in the employment as a depolarizer, of the protosulfid of copper Cu_2S .

As is known, protosulfid of copper can be obtained by the combustion of copper sheets in sulfur vapor away from contact with the air.

In carrying out the invention in practice, I proceed as follows to form a depolarizing element:—The protosulfid of copper hav-

ing been obtained preferably in the manner above indicated, I break it into small pieces which I place in a cylinder of wire cloth (say copper) disposed around a metallic rod (say copper) which forms the axis of the depolarizer. The cylindrical element thus obtained will form a voltaic couple with zinc, having a concentrated solution of caustic soda as an electrolyte. The said couple has an E. M. F. of 0.7 volt and is 30 almost unpolarizable.

What I claim as my invention and desire to secure by Letters Patent is:

A depolarizer for batteries comprising artificial protosulfid of copper, and a container for said protosulfid of copper.

Signed at New York city, in the county of New York and State of New York this twenty-first day of February, A. D. 1916.

FELIPPE SABOIA BANDEIRA DE MELLO.
